UNITED STATES PATENT OFFICE

MORTON F. PHELPS, OF LITTLE ROCK, ARKANSAS, ASSIGNOR TO PHELPS MANUFACTURING COMPANY, A COPARTNERSHIP CONSISTING OF FRANK PHELPS AND MORTON F. PHELPS, OF LITTLE ROCK, ARKANSAS

EXHAUST FAN

Application filed March 10, 1926. Serial No. 93,630.

The purpose of this invention is to provide a perforated disk or screen member for use with blast wheels, and so arranged that it may be applied or removed from the wheel without interfering with the running balance of the latter. It consists in certain features and elements of construction herein shown and described as indicated by the claims.

10 In the drawings:—

Figure 1 is a side elevation of a blast wheel or blower of the type to which this invention is applied.

15 Figure 2 is a perspective view of the same with part of the casing broken away to show interior construction.

Figure 3 is a vertical axial section taken through the assembled wheel and screen disk, but with some of the wheel paddles removed.

20 Figure 4 is a side elevation showing the hub and a fragment of the perforated disk as applied to the shaft of the wheel.

Figure 1 illustrates a typical blast wheel 25 comprising a base casting, 1, having journal bearings, 2, 2, which carry the shaft, 3, and its drive pulley, 4. On the projecting end of the shaft is secured the hub, 5, of the blast wheel, while the blades or paddles, 30 6, are attached to radial ribs, 5^a, of the hub by extending arms, 7, of flat stock riveted to the ribs, 5^a, and to the blades. This wheel is mounted to revolve in the casing comprising side walls, 8, 8, tied together by bolts, 9, which are arranged adjacent the edges of the side plates, 8, and just outside the peripheral wall, 10, which is thus clamped between the side plates. The casing is formed with the usual outlet or discharge opening, 11, and inlet, 12, the latter being concentric with the end of the shaft, 3.

40 Heretofore, when the character of the work has required a screen or perforated disk to be applied to the blast wheel at the inlet side, such a disk has been attached by means of lugs or ears engaging the outer edge of the disk with the blades of the wheel, and such assembly was then placed in running balance in order to insure smooth 45 operation. However, this mode of construc-

tion requires rebalancing whenever the screen is removed and replaced.

In accordance with the present invention, the perforated screen disk, 13, is secured to a central hub, 14, which is bored to fit the 55 end portion of the shaft, 3, which protrudes beyond the hub, 5, of the blast wheel proper. In the arrangement shown, the blast wheel hub, 5, is made fast to the shaft, 3, by means of a key, 15; therefore, the hub, 14, is 60 formed with a groove, 16, dimensioned to fit over the projecting end of the key, 15, so that the latter will not interfere with mounting the screen, 13, on the shaft. At the opposite side the hub, 14, is provided with a 65 set screw, 17, for tightening the hub, 14, in position, though it will be evident that the end portion of the key, 15, will readily serve to transmit the driving torque to the screen disk, 13. The screen disk, 13, assembled with 70 its hub, 14, and set screw, 17, is balanced with respect to the axis of its central bore before it is placed on the shaft, 3, and the blast wheel itself is individually balanced on the shaft before the screen disk is applied. Thus when the disk becomes worn or 75 is to be replaced for any other reason, it is only necessary to loosen the set screw, 17, and remove it while a substitute disk, also previously balanced, may be quickly set in 80 its place.

I claim:—

1. In a power driven blast wheel including a casing formed with a discharge opening and in one side with an inlet, the combination of a shaft and means for applying power thereto, a fan wheel fixed to the shaft and a screen comprising a disk and a central hub to which it is secured and by which it is fixed to the shaft independently of the 90 fan wheel, said screen disk being prebalanced for rotation about the axis of its hub and disposed between the blast wheel and inlet opening in the side of the casing to separate solid matter from air drawn 95 through the inlet opening and screen and prevent such solid matter from contact with the blast wheel blades, and said casing having a removable side whereby said screen is removable and replaceable by another pre- 100

balanced screen without disturbing the balance of the blast wheel.

2. In an exhaust fan comprising a casing formed with a discharge opening and in one side with an inlet; a power driven shaft extending into the casing, a balanced fan wheel within the casing and secured to the power driven shaft, an independently pre-balanced screen secured to the power shaft and disposed between the fan wheel and side of its casing formed with the inlet, to separate solid matter from air drawn through the screen and prevent such solid matter from contact with the fan wheel blades, the casing having a removable side whereby said screen is removable and replaceable by another prebalanced screen without disturbing the balance of the fan wheel.
